US0D1105105S

(12) **United States Design Patent** (10) Patent No.: **US D1,105,105 S**
Herman et al. (45) Date of Patent: ** Dec. 9, 2025

(54) **DISPLAY SCREEN OR PORTION THEREOF
WITH GRAPHICAL USER INTERFACE FOR
A SEED FURROW**

(71) Applicant: **DEERE & COMPANY**, Moline, IL
(US)

(72) Inventors: **Carolyn R. Herman**, La Porte City, IA
(US); **Jason C. Mauer**, Wes Des
Moines, IA (US)

(73) Assignee: **Deere & Company**, Moline, IL (US)

(**) Term: **15 Years**

(21) Appl. No.: **29/907,342**

(22) Filed: **Jan. 5, 2024**

(51) LOC (15) Cl. **14-04**

(52) U.S. Cl.

USPC **D14/485**

(57) **CLAIM**

The ornamental design for a display screen or portion thereof with graphical user interface for a seed furrow, as shown and described.

DESCRIPTION

FIG. 1 is a front view of the display screen or portion thereof with graphical user interface for a seed furrow, according to a first embodiment of our claimed design; and,

FIG. 2 is a front view of the display screen or portion thereof with graphical user interface for a seed furrow, according to a second embodiment of our claimed design.

(Continued)

2.3 in

The dot-dash broken lines illustrate the display screen or portion thereof and form no part of the claimed design. The dash-dot broken lines illustrate portions of the graphical user interface that form no part of the claimed design.
